(57) **CLAIM**

The ornamental design for a color temperature sensor, as shown and described.

DESCRIPTION

FIG. 1 shows a top perspective view of a color temperature sensor.

FIG. 2 shows a top plan view of the color temperature sensor.

FIG. 3 shows a front elevational view of the color temperature sensor.

FIG. 4 shows a rear elevational view of the color temperature sensor.

FIG. 5 shows a left side elevational view of the color temperature sensor.

FIG. 6 shows a right side elevational view of the color temperature sensor; and,

FIG. 7 shows a bottom plan view of the color temperature sensor.

The broken lines in the figures depict portions of the color temperature sensor that form no part of the claimed design.
